UNITED STATES PATENT OFFICE.

JOHN BAILEY BROWNING, OF CAMDEN, NEW JERSEY, ASSIGNOR, BY MESNE ASSIGNMENTS, OF FIFTY-ONE ONE-HUNDREDTHS TO THE BRUNSWICK-BALKE-COLLENDER COMPANY, A CORPORATION OF DELAWARE.

TALKING-MACHINE CABINET AND AMPLIFIER.

1,402,738.

Specification of Letters Patent. Patented Jan. 10, 1922.

Original application filed January 18, 1908, Serial No. 411,454. Divided and this application filed August 17, 1921. Serial No. 492,936.

To all whom it may concern:

Be it known that I, JOHN BAILEY BROWNING, a citizen of the United States, residing at the city of Camden, in the county of 5 Camden and State of New Jersey, have invented new and useful Improvements in Talking-Machine Cabinets and Amplifiers, of which the following is a specification.

My invention relates more particularly to 10 sound reproducing or talking machines having an enclosed horn or amplifier to which the sound is transmitted through a suitable sound conduit from the sound-box or sound reproducing means.

15 In the drawings: Fig. 1 is a sectional side elevation of a machine embodying my invention; Fig. 2 is a front elevation of the same on a reduced scale and with the front doors open; Fig. 3 is a rear elevation; Fig. 20 4 is a vertical section of the collar for securing the horn section to the opening in the back of the cabinet; Fig. 5 is a side elevation of the turn-table brake; Fig. 6 is a plan view of the brake escutcheon; Fig. 7 25 is a longitudinal section of the turn-table brake; Fig. 8 is an inverted plan view of the cabinet and Fig. 9 is a vertical section on line α — α of Fig. 8 with the position of the cabinet reversed.

30 1 is the table upon which the usual talking machine rests. 3 is a bracket secured to the rear of the talking machine which supports the removable arm 4 which in turn carries the sound box 5 which operates upon 35 the disc 15 supported on the turn-table 7 and centered by means of the pin 6. 6 $\times$ is the handle for operating the motor of the machine. 8 is a horn section carried by the bracket 3 and communicating with the sound 40 arm 4. The parts 4 and 8 together constitute a sound passageway extending from the sound box. Supported on top of the machine 2 is a cabinet divided by a horizontal partition 12 into two compartments, the 45 lower compartment 13 enclosing the rotating disc and sound box, and the upper compartment being divided by partitions 10, 11, 11 $\times$ into a tapered amplifier, the small end of which opens at the rear through the back 50 of the cabinet and communicates with the portion 8 of the sound passageway which may be connected with the rear of the cabinet by means of the clamp 18—19, which

as shown is made in two sections connected by screws 20.

55 The walls 10, 11, 11 $\times$ and 12 which extend from the rear opening to the front of the cabinet form a tapered amplifier which opens at the front of the cabinet through adjustable doors 32 which may be adjusted by suitable handles 35, and there are thus formed between the side walls of the cabinet and the side walls 11, 11 $\times$ of the amplifier, resonance chambers 16—17, and the side walls of the cabinet are 60 provided with doors 36—37, by the adjustment of which, as shown in Fig. 8, the resonance chambers may be adjusted and outlets may be provided at the front.

65 Between the top of the amplifier 10 and the top 9 of the cabinet is also formed a resonance chamber 14, and this may be used, if desired, as a storage space for records 15, as shown in Fig. 1. Records may also be placed upon the base 12 in the amplifier 14 $\times$. 70

75 The sound arm 4 extends through an oblong aperture 22 in the back of the lower compartment of the cabinet, and this oblong opening is closed by a movable plate 23 provided with an opening 27 through which the 80 arm 4 extends. The plate is held in position with freedom of movement by springs 24 between pins 26 on the plate and 25 on the frame of the cabinet. The movement of the plate may be regulated by the adjustment of the tension of the springs 24, so that the arm may move freely while keeping the aperture 22 substantially closed.

85 38 is a brake extending through an escutcheon 42 in the back of the cabinet and 90 provided on the end with a friction pad 41 of leather, felt or equivalent material adapted to make contact with the periphery of the turn-table. The brake is provided with a spring 40 between the pin 39 and the 95 escutcheon, and the latter is provided with an elongated slot 43 so that when the pin is turned into the transverse position it will be held retracted out of contact with the turn-table.

100 The lower compartment 13 of the cabinet is provided at the front with doors 30 which may be opened, closed or adjusted to control the emission of sound from said lower compartment. The cabinet is preferably made 105 separable from the body of the machine 2

and may be attached by the clamp 28 and set screw 29 as shown in Fig. 1.

It will be noted that the cabinet is divided into two compartments, one enclosing the rotating disc and sound box and the other of which contains an amplifier, and that the sound passageway between the sound box and the amplifier extends outside of the cabinet entering the small end of the 10 amplifier at the rear of the upper compartment of the cabinet.

This amplifier is formed in two sections, one of which is movable and the other fixed. In the particular construction shown the 15 movable member is the lower portion 4 which moves with the sound box over the record, while the fixed portion is the upper part 8 which is attached by the bracket 18-19 to the upper part of the cabinet. 20 The parts 4 and 8 constitute a means of communication between the sound reproducing means and sound amplifying means extending outside of the cabinet and comprising a fixed hollow member and a movable hollow member communicating therewith.

The walls of the amplifier are enclosed in a resonance chamber or chambers which may be opened, closed or adjusted by the regulation of the enclosing walls. While 30 I prefer the details of construction shown they may be varied without departing from the invention.

This application is filed as a division and continuation of my application Serial No. 35 411,454, filed January 18, 1908.

What I claim is as follows:

1. The combination with sound reproducing means, of a co-operating amplifier, a cabinet enclosing the major portion of 40 said amplifier and provided with an opening of substantially the same size as the delivery end of said amplifier, and means to vary the quality of the reproduction at will on either side of said cabinet.

45 2. In a talking machine, the combination of a cabinet provided with a sound chamber, sound reproducing means carried by said cabinet outside of said chamber and communicating with said chamber, and a 50 pair of inflexible doors in said cabinet controlling the exit of sound.

3. In a talking machine, the combination of a cabinet provided with a chamber, sound reproducing means carried by said cabinet 55 outside of said chamber, an amplifier enclosed within said chamber and communicating with said reproducing means, and a pair of inflexible doors in said cabinet for controlling the exit of sound.

60 4. In a talking machine, the combination of a cabinet provided with a sound chamber, sound reproducing means carried by said cabinet outside of said chamber and communicating with said chamber, and a 65 plurality of swinging inflexible deflectors

connected to said cabinet and controlling the exit of sound from said chamber.

5. In a talking machine, the combination of sound reproducing means, a sound amplifier communicating therewith, and two 70 swinging inflexible deflectors adjacent the mouth of the amplifier controlling the amplified sound.

6. In a talking machine, the combination of a cabinet, sound reproducing means carried by said cabinet, a sound amplifier communicating with said reproducing means and enclosed within said cabinet and having communication with the atmosphere, and means on either side of said cabinet to 80 modify the sound.

7. In a talking machine, the combination of a cabinet provided with a sound chamber, sound reproducing means carried by said cabinet outside of said chamber and 85 communicating with said chamber, said chamber having an exit opening, and a plurality of swinging deflecting members mounted in said exit opening and controlling the sound.

90 8. In a talking machine, the combination with a sound reproducing means, of a co-operating amplifier, a cabinet enclosing the major portion of said amplifier and provided with a plurality of separated 95 resonance chambers between the enclosing walls of the cabinet and the walls of the amplifier.

9. In a talking machine, the combination with sound reproducing means, of a co-operating amplifier, a cabinet enclosing the major portion of said amplifier, and a hollow rigid bracket carried by the outside of 100 said cabinet and communicating with the sound reproducing means and with the amplifier.

10. The combination with a cabinet, of a record support in said cabinet, sound reproducing means and sound amplifying means extending in said cabinet above said 110 record support, and means of communication between said sound reproducing means and said sound amplifying means extending outside of said cabinet and comprising a fixed hollow member and a movable hollow 115 member communicating therewith.

11. The combination with a cabinet, of a record support in said cabinet, sound reproducing means and sound amplifying means extending in said cabinet above said 120 record support, and means of communication between said sound reproducing means and said sound amplifying means extending outside of said cabinet and comprising a fixed hollow member communicating with 125 said sound amplifying means, and a movable hollow member communicating therewith and with the sound reproducing means.

12. A cabinet for talking machines divided into two chambers, the lower chamber 130

being open at the bottom and adapted to enclose the sound reproducing means, and the upper chamber containing a sound amplifier and having adjustable side walls by 5 which the space between the side walls of the amplifier and the enclosing walls of the chamber may be adjusted, in combination with a talking machine having its sound reproducing devices enclosed by the lower 10 chamber of said cabinet, and a sound conduit leading outside of the cabinet from the sound reproducing means in the lower chamber thereof to the sound amplifier in the upper chamber, and consisting of two 15 hollow portions one of which is movable with respect to the other.

13. A cabinet for talking machines divided into two chambers, the lower chamber being open at the bottom and adapted to 20 enclose the sound reproducing means, and the upper chamber containing a sound amplifier and having adjustable side walls by which the space between the side walls of the 25 chamber may be adjusted, in combination with a talking machine having its sound re-

producing devices enclosed by the lower chamber of said cabinet, and a sound conduit leading outside of the cabinet from the sound reproducing means in the lower chamber thereof to the sound amplifier in the upper chamber, and consisting of a movable hollow portion connected with the sound reproducing means and extending out of the lower chamber, and a fixed hollow portion connected with the small end 35 of the sound amplifier in the upper chamber.

14. A talking machine mechanism comprising a motor casing having a top provided with an outwardly extending and overhanging top portion, and a cabinet having its lower edges resting upon said top, fastening means upon said cabinet engaging with and beneath said overhanging top portion, and sound reproducing and conveying means extending outwardly from within said cabinet.

Signed at the city, county and State of New York, this 30th day of July, A. D. 50
1921.

JOHN BAILEY BROWNING.
